United States Patent Office

Des. 232,509
Patented Aug. 27, 1974

232,509

PILLOWCASE OR SIMILAR ARTICLE OF BED LINEN

Nancy Ann Scherer, Plainfield, N.J., assignor to Cannon Mills Company, Kannapolis, N.C.

Filed Nov. 2, 1972, Ser. No. 303,120

Term of patent 14 years

Int. Cl. D6—13

U.S. Cl. D6—264

The figure is a plan view of a pillowcase showing my new design, the side opposite thereto being substantially identical.

I claim:

The ornamental design for a pillowcase or similar article of bed linen, substantially as shown.
